UNITED STATES PATENT OFFICE.

THOMAS G. CONCANNON AND LESLIE W. PETERSON, OF EMPORIA, KANSAS; SAID PETERSON ASSIGNOR TO SAID CONCANNON.

MANIFOLD HEATING DEVICE.

Application filed November 5, 1920. Serial No. 421,922.

To all whom it may concern:

Be it known that we, THOMAS G. CONCANNON and LESLIE W. PETERSON, citizens of the United States, residing at Emporia, in 5 the county of Lyons and State of Kansas, have invented a certain new and useful Improvement in Manifold Heating Devices, of which the following is a specification.

Our invention relates to improvements in 10 manifold heating devices.

The object of our invention is to provide novel means by which the intake manifold of an explosive engine may be heated from the exhaust manifold of the engine.

15 Our invention provides further a novel heat conducting plate adapted to be clamped against the intake and exhaust manifolds of an explosive engine for conducting heat from the exhaust manifold to the intake 20 manifold.

Our invention provides further a heat conducting plate of substantial body, which is cheap to make, which is durable, which may be easily and readily applied by an un- 25 skilled person to the manifolds of an engine now in use, and which is adapted to be attached to the manifolds by the clamping mechanism now used for clamping the manifolds to the engine body, and without change 30 of mutilation of the engine structure, and which will equally heat the branches of the intake manifold which lead to the different intake ports.

The novel features of our invention are 35 hereinafter described and claimed.

In the accompanying drawing which illustrates the preferred embodiment of our invention,

Fig. 1 is a side elevation of a portion of 40 an explosive engine provided with our improvement.

Fig. 2 is a vertical section on the line 2—2 of Fig. 1.

Fig. 3 is an inside elevation of the heat 45 conducting plate.

Fig. 4 is a horizontal section on the line 4—4 of Fig. 1.

Similar reference characters designate 50 similar parts in the different views.

1 designates the body of an explosive en- 55 gine of a type now in common use and 2

and 3 the intake and exhaust manifolds of the same.

As ordinarily constructed the manifolds 2 and 3 are clamped to the body 1 by means 55 of four horizontal clamping plates 4, which are respectively mounted on four horizontal outwardly extending bolts 5, the inner ends of which are attached to the engine body 1 and the outer screw threaded ends 60 of which have respectively mounted on them nuts 6 which respectively bear against the outer sides of the clamping plates 4. As ordinarily used the clamping plates 4 are so arranged that each plate bears against 65 adjacent portions of the two manifolds in a manner well known.

7 designates our improved heat conducting plate which is of substantial body and approximately rectangular in form and 70 which is adapted to be disposed intermediate of the two inner bolts 5, and which is adapted to fit snugly and bear against the outer sides and middle portions of the manifolds 2 and 3.

The outer side of the plate 7, is preferably 75 provided adjacent to its right and left edges respectively with two recesses 8 which are adapted to respectively receive the adjacent ends of the two inner clamping plates 4. 80 These two clamping plates serve to securely clamp the plate 7 against the outer sides of the manifolds 2 and 3 in addition to their function of clamping the manifolds to the engine body 1.

For facilitating the conduction of heat 85 from the exhaust manifold 3 to the intake manifold 2, the middle portion of plate 7 is provided with an inwardly extending projection 9 of substantial thickness and body, 90 which projection is adapted to be disposed between and fit against the two conducting portions 10, of the exhaust manifold which respectively lead from the two inner exhaust ports 11 of the engine body.

The inner side of the plate 7 is formed to 95 fit the outer sides of the manifolds 2 and 3.

In the type of engine referred to, the manifold 2 is provided with two lateral branches which lead to the intake ports of 100 the engine, said intake ports being designated by 12, Fig. 4. The plate 7 covers equal

portions of the two branches of the intake manifold 2, so that these two branches are heated by the plate 7 to substantially the same degree.

5 In applying our invention to the type of engine referred to, the two inner nuts 6, and the two inner plates 4 are removed from the bolts 5 which support them, after which the plate 7 is mounted in position against the manifolds 2 and 3 and between the two inner bolts 5. The removed plates 4 are then replaced on the two inner bolts 5 in a manner such that their outer ends will bear against the two branches of the intake manifold and with their inner ends mounted respectively in the recesses 8 and bearing against the outer side of the plate 7.

10 The two removed nuts 6 are then replaced upon the bolts 5, and are tightened, so that 20 the plate 7 will be tightly clamped by the two adjacent plates 4 to the outer sides of the manifolds 2 and 3.

15 The heat from the exhaust manifold 3 will be conducted by the plate 7 to the intake manifold 2, which will thus heat the incoming explosive mixture, thus, in a manner well known, increasing the efficiency of the engine and affording a large reduction in the amount of fuel required.

20 In the application of our improvement, no alteration of the engine structure or other parts is required and an unskilled person can quickly and easily apply the heating plate to the engine.

25 We do not limit our invention shown and described, as modification, within the scope

of the appended claims may be made without departing from the spirit of our invention.

What we claim is:—

40 1. In a manifold heating device, the combination with an engine body, an intake manifold having two branches, an exhaust manifold having two branches, two bolts attached to the engine body, and two clamping plates respectively mounted on said bolts and respectively bearing on the outer sides of the branches of the intake manifold, of a heat conducting plate of substantial body, held by the two clamping plates against the outer sides of the two manifolds intermediate of the ends of the branches of the intake manifold and having at its inner side a projection fitted between and against the two branches of the exhaust manifold, substantially as set forth.

45 2. A manifold heating device comprising, a heat conducting plate of substantial body, adapted to embrace the outer sides of an exhaust manifold and an intake manifold and 50 provided on its outer side at its side edges, with two recesses adapted to receive respectively two clamping plates, and provided on its inner side, intermediate of and in alignment with said recesses, with an inwardly extending projection adapted to fit between and against the intake and exhaust manifold, substantially as set forth.

55 In testimony whereof we have signed our names to this specification.

THOMAS G. CONCANNON.
LESLIE W. PETERSON.
